UNITED STATES PATENT OFFICE.

DAVID VICTOR REEVES, OF EAST DEDHAM, MASSACHUSETTS.

SUBMARINE LIFE-BOAT.

1,210,840.

Specification of Letters Patent. Patented Jan. 2, 1917.

Application filed April 19, 1915. Serial No. 22,222.

To all whom it may concern:

Be it known that I, DAVID VICTOR REEVES, a citizen of the United States, and resident of East Dedham, county of Norfolk, State of Massachusetts, have invented an Improvement in Submarine Life-Boats, of which the following description, in connection with the accompanying drawing, is a specification, like characters on the drawing representing

10 like parts.

This invention relates to improvements in submarine life boats and the object thereof is to produce a life boat which may be rigidly attached to a ship whether a merchant's liner, passenger vessel or submarine craft and provided with means whereby the persons upon a sinking ship may pass to the life boat either before or after the ship sinks and after the ship is submerged may release 20 the life boat and permit the same to rise to the surface.

Another object of the invention is to provide a life boat of the character described with propulsive equipment adapted to be actuated either by power such as an internal combustion engine or by hand and also to provide said life boat with an equipment whereby air may be supplied to the submerged vessel for the purpose of maintaining 30 the lives of people who may have failed to enter the life boat or for the purpose of supplying air to the submerged ship to float the same.

Another object of the invention is to provide 35 a means whereby the life boat may be returned to the sunken vessel and communication again made with the interior of the airtight compartment of the ship.

Another object of the invention is to provide 40 life boats of the character above described of such construction that they may be used as a portion of the ship to which they are attached, for example if the life boats form a part of the equipment of a passenger vessel they may be so arranged in respect to 45 the staterooms as to form a suite or if used upon a submarine vessel may be so located as to be utilized as the conning tower.

Other objects of the invention will be more 50 fully described in the following description and particularly pointed out in the appended claims.

Figure 1 is a vertical longitudinal sec-

tional view of a life boat embodying a preferred form of the invention, also illustrating the life boat as attached to the deck of a vessel, Fig. 2 is a horizontal sectional view of the life boat illustrated in Fig. 1, Fig. 3 is a vertical sectional view of a submarine life-boat showing in section the upper deck of a submarine vessel to which the submarine life boat is attached, Fig. 4 is a detail view of the hatch closing mechanisms for the ship and submarine, Fig. 5 is a detail plan view of the life boat hatch showing in dotted lines the 65 automatic closure for the hatch of the main ship, Fig. 6 is a longitudinal vertical sectional view of the same, Fig. 7 is a plan view of a submarine with two life boats superposed on the deck thereof in alinement and 70 showing a connection between the conning tower of the submarine and the stern of one of the life boats, Fig. 8 is a vertical transverse sectional view of a nest of submarine life boats attached to the deck of a ship, and 75 Fig. 9 is a plan view of a passenger vessel equipped with a series of submarine life boats of the character above described which are accessible from the staterooms of the ship.

It has been demonstrated in recent years that the usual type of open life boats is wholly inefficient and inadequate to protect the lives of the people who yearly travel the ocean and inland waterways, since frequently vessels sink before the life boats can be launched or when the life boats are launched in a heavy sea they are frequently crushed against the side of the ship or upset, thus precipitating the occupants into the 85 water.

Furthermore, so far as I am aware no life boats have heretofore been devised for use upon submarine vessels. The necessity of such life boats has been demonstrated frequently within the last few years, since several submarines have sunk to the bottom of the ocean and the occupants being unable to escape have been drowned or suffocated.

The present invention is intended to provide means whereby the occupants of any vessel, whether of the surface type or the submarine, may be saved even after the vessel has become submerged.

The preferred form of life boat which is 105 illustrated in the accompanying drawings

comprises an inclosed body portion which preferably is substantially cylindrical in form and has a substantially hemispherical stern 2 to present the greatest possible amount of rigidity under compression. The bow 3 of the life boat may however be tapered as illustrated in Fig. 2 to present a suitable prow for cutting the waves. In such case a transverse bulkhead 4 desirably 10 may be provided to strengthen the bow portion, said bulkhead being also adapted to serve as the wall of a fuel tank 5 which may be provided with a tight cover 6 and a screw cap 7 through which liquid fuel may be introduced into the tank. 15

The life boat desirably is equipped with motive power preferably in the form of a gasoline engine 8 connected to the shaft 9 of a propelling screw 10, a removable portion 20 of the shaft being connected by detachable universal joints 12-13 to the motor. A shaft 9 provides means for driving the life boat by hand power. The shaft 11 is removable to permit free access to the 25 hatch hereinafter to be described and also to provide means whereby the boat may be propelled by hand by a suitable crank 14 connected by gears or a chain drive 15 to the shaft 9. By thus providing means for 30 driving the life boat by hand the boat may be propelled in rising so as to avoid obstructions. The hand power may also be used if the life boat is returned to the ship to position the hatches of the same properly in 35 registration with the hatches upon the ship. The life boat will of course be provided with a rudder 16 preferably having its stem 17 extending through the hull of the life boat and provided with a quadrant steering 40 handle 18. The life boat may also be equipped with a steering wheel 19 mounted upon the bulkhead 4 and connected by lines or chains in any suitable manner with the rudder aforesaid. 45

A suitable protecting cage (not shown) may be provided for the rudder and screw and so attached to the hull of the life boat that it may be detached from within after the life boat has reached the surface. 50 The body of the life boat is desirably provided with a plurality of lateral ingress openings 20, top openings of like character and preferably two bottom ingress openings 21-22. These openings may be of any suitable character, either round, rectangular or oblong but preferably are circular in order to provide the maximum space. They are provided with suitable hermetic closures which preferably are in the form of hinged doors 23 which may be secured in place by suitable bolts 24 or other fastenings. 60

Usually the submarine life boat will be secured to the deck of the vessel and means will therefore be provided which will per-

mit the entrance of passengers through the 65 bottom of the life boat. As illustrated herein the submarine life boat is secured to the deck of the vessel preferably by a series of long bolts 25 which pass through reinforced plates 26 surrounding an annular hatchway 70 27 in the life boat said bolts extending into a similar thickened or reinforced plate 28 of the same size and form surrounding the hatchway 29 in the deck 30 of the main ship or submarine. 75

It will therefore be obvious that the hatchway in the bottom of the life boat will register with the hatchway in the deck of the main vessel so that the hatchway of the main vessel will provide a means of egress 80 and that in the life boat a means of ingress for passengers who pass from the one to the other.

The ingress passage or hatch of the life-boat is provided with a hermetically tight 85 closure preferably in the form of a plate 31 which may be provided with a hinge 32 securing the same to the annular plate 26 and may be provided with suitable permanent packing to hermetically seal the hatchway 90 when the plate 31 is closed.

In order to provide means for quickly clamping the plate 31 in position a slot 33 is provided opposite the hinge, said slot being adapted to receive a bolt 34 suitably pivoted 95 in the plate 26 and provided with a winged clamping nut 35. The plate 31 will also be provided with a series of clamping bolts 36 by which the same may be permanently secured to the flange 26 thus rendering the 100 bottom of the life boat air and water tight.

The ingress opening of the lifeboat preferably connects with an air tight compartment of the main ship which may be closed off in such a manner that the passengers 105 which are assembled there will have additional time in which to enter the life boat and also to provide means whereby the air which is within the ship may be retained therein to assist in raising the ship. I have 110 therefore provided means for closing the hatchway 29 of the main vessel and hermetically sealing the same so that after the life boat has been detached the air chamber will still remain filled with air. A preferred means for closing the hatchway of 115 the main ship comprises a plate 40 having a hinge 41 connecting the same to a thickened flange 28. The hinge 41 preferably is practically beneath the hinge 32 in the life boat 120 hatch so that the cover plates 31 and 40 both open upwardly into the body of the submarine life boat when the hatchway is opened. By this construction it is obvious that in order to close the ingress hatchway 125 27 of the life boat it is necessary first to close the exit hatchway 29 of the main ship. The cover plate 40 will be provided with a

series of bolts 42 by which the same may be clamped firmly against the supporting ledge 43.

In order to insure a more perfect closure of the egress opening of the hatchway of the main vessel I have provided an additional automatic closure for the hatch or an auto hatch which will be thrust into closed position when the submarine life boat is released from the main ship. As illustrated herein this closure comprises a wedge shaped plate 44 mounted in suitable ways on the under side of the deck 30, the plate being provided with a depending arm or stud 45 which is attached to a cable 46 passing from a pulley 47 supported in overhanging bearings 48 and provided at its end with a counterweight 49 adapted normally to pull the plate 44 into closed position. A suitable wedge shaped seat 50 is provided beneath the hatchway into which the plate 44 is adapted to be thrust upon its release, said seat serving to force the plate 44 tightly against the under wall of the hatchway.

The wedge shaped plate 44 is normally retained in retracted position by the bolts 25 which pass down through the bottom of the life boat into the deck of the ship or submarine the bolts 25 being of a sufficient length to extend in the path of the wedge shaped plate 44.

It will be obvious therefore that when the bolt 25 is withdrawn the wedge shaped plate will be released and will be forced by the counterweight 49 into the seat 50, thus tightly closing the hatchway from beneath.

In order to prevent water from entering the main ship after the bolts 25 have been withdrawn to release the life boat suitable valves may be provided to cover the bolt holes. A ball valve for this purpose is illustrated herein which comprises a ball 51 seated in a suitable recess 52 in the thickened portion or flange 28 of the deck of the vessel, the ball being adapted to roll into position above the bolt hole upon the removal of the bolt 25 and to prevent water from entering the vessel. The ball will be retained in its seat by the external pressure of the water.

In order that the bolts 25 may be readily inserted the ball 51 is made of a diameter considerably in excess of the diameter of the bolt so that when the hatchways 27 and 29 are superposed and the bolts 25 thrust downward they will strike tangentially upon the ball and roll it from closing position and thereby permit the bolt 25 to be thrust into engagement with its bolt hole in the deck of the main ship.

It is desirable where the life boat is used upon a submarine vessel to provide means whereby the submarine may be supplied with air from the life boat after the latter has risen to the surface, either to float the same

or to maintain the lives of such persons as 65 may be left in the submarine. For this purpose the submarine life-boat may be provided with means for reeling up and for hoisting an air hose which may be suitably connected to the submarine or to the air 70 tight compartments of the ship. It is also desirable that means may be provided for connecting the life boat to the ship which may be used either to raise the sunken vessel, if not waterlogged, or to provide means 75 whereby the submarine lifeboat may be returned to the sunken vessel as a diving bell. In order to provide such means I have provided the life boat with preferably two compartments 53, 54 one being located forward 80 and the other aft of the center of the life boat, said compartments being watertight and provided with suitable hand holes 55 by which access may be had to their interior. These compartments are provided with two 85 sets of windlasses 56 and 57 the windlasses 56 serving to support an air hose or a line suitably attached to an air hose and windlass 57 supporting a cable 58 or a line fastened to a cable.

The cable 58 may be suitably secured to the deck or frame of the vessel and may if desired be coiled upon the deck of the ship or submarine the end only of the cable or a line attached thereto extending within the 95 chamber 54 and being attached to the windlass. The air hose 59 may desirably extend from the windlass to the deck of the submarine or vessel and there be attached by suitable couplings to a permanent air pipe 100 60 leading to the interior of the vessel. The pipe 60 may be provided with suitable check valves 61 and automatic valves 62 which will be operated by the mechanism releasing the plate 44 to establish air connection between 105 the air hose 59 and the interior of the sunken vessel when the submarine is released. Two different mechanisms for this purpose are illustrated. In Fig. 1 of the drawing, the forward hatch closing plate is provided with 110 a laterally hooked tongue 63 which is adapted to engage a lever 64 of the valve 62 and thereby open the valve when the auto hatch 44 is released. In the construction shown at the rear hatchway the weight 49 engages the 115 lever 64 of the valve 32 upon the release of the auto hatch 44.

It will thus be seen that the hose connection between the submarine and the life boat will be at once effected when the life boat is 120 cast away from the ship. When the boat has risen to the surface the end of the hose may be drawn through the hand hole 55 in the windlass compartment 54 and attached to a suitable air pump 65 which may be actuated 125 either from the engine upon the life boat or by hand.

Suitable compressed air tanks 66 may be

supported in the central portion of the life boat and provided with connections leading to the windlass compartments 54 so that the water may be expelled therefrom when the windlass is to be used. The compressed air may also be used if necessary to prevent suffocation of the occupants while the same is submerged, although it is to be understood that the lifeboat will be equipped with oxygen apparatus or oxygen tanks of sufficient capacity to maintain the lives of the occupants for several hours.

In order to adapt a life boat of the character above described to a submarine which is adapted to travel at least a portion of the time beneath the surface of the water I have devised means whereby one or more life boats may be placed upon the submarine in such a manner as not to impede the progress of the submarine and also to provide a means whereby the life boat itself may be used as a lookout or conning tower. Such constructions are illustrated in Figs. 3 and 7. The deck 30 of the submarine is provided with a depression or recess 67 into which the hull 1 of the life boat may fit. The life boat and the submarine have the same form of hatches as above described and the same reference numerals are applied in these figures to like parts.

As illustrated in Fig. 3 a single life boat may be attached to the deck of the submarine and may serve as a conning tower, suitable bull's eyes 68 being provided forward and aft and if desired at the sides for the purpose of permitting the officers to take observations after rising to the surface. These bull's eyes may of course be provided with suitable cover plates which will hermetically seal the same and prevent breakage of the glass when the lifeboat is submerged.

In Fig. 7 I have illustrated two life boats similarly supported upon the deck of a submarine, one in front of and the other aft of the conning tower. These life boats may be accessible through hatchways in the bottom as above described and also may be provided with doors at the end connecting with the conning tower.

In Fig. 7 I have shown suitable apertures 20^a with cover plates 21^a by which access may be had from the stern of one of the life boats to the conning tower and it will be readily understood that similar means of access may be had to the other life boat or that the life boat may be placed upon the submarine in reversed position so that the stern of both life boats shall rest against the conning tower and be secured thereto in the manner aforesaid.

In view of the fact that the preferable form of life boat is cylindrical and the space therein necessarily restricted it is desirable that the life boat be provided with a deck,

This may be accomplished by providing the sides of the life boat with laterally extending lugs or projections 70 adapted to receive the screw threaded ends of stanchions 71 which may support the outer ends of suitable deck beams 73, preferably in the form of T-beams resting at their inner ends upon the body 1 of the life boat and secured thereto by suitable bolts. The stanchions may be provided at their tops with rings 74 to receive life lines extending from the forward to the aft end of the boat.

It will be understood that the life boat will be provided with the necessary equipment for such voyage as may be necessary. I have therefore made provisions for lockers 75, 76 at the ends of the life boat, water tanks 77 or lockers and tanks being so disposed as to take up a minimum room within vessel and to leave sufficient space preferably through the center of the vessel for hammocks and other accessories for the convenience of the occupants. The life boat may be provided above the water line with suitable port holes 78 which may be closed with cover plates as aforesaid.

In order to conserve the power of the life boat I have provided a step 79 for a jury mast (not shown) which may be in sections of such lengths as to be conveniently stored within the life boat and which may be erected and lashed to suitable wings not shown upon the deck or sides of the life boat.

In Fig. 8 I have illustrated a nest of life boats of the character above described piled one upon the other. In this construction the deck of the main vessel is provided with egress openings so spaced that the adjacent walls of the life boats 80, 81, and 82 will come in contact and may be securely bolted or lashed together. In this construction the passages 84 may be provided from one life boat to another so that when the whole are assembled they may form a single raft or if desired each life boat may be used separately. Other life boats 85, 86, and 87 may be superposed upon the life boats 80, 81, 82 if desired so that such number of intercommunicating life boats may be provided as may be necessary for a passenger ship.

In Fig. 9 I have illustrated a further modification showing additional uses to which this invention may be placed. In this figure a series of life boats 90 of the character above described are illustrated as supported upon the deck of a passenger vessel and so arranged that the lateral openings 20 will lead to staterooms 91. The life boats may therefore form a part of a suite of staterooms and may be equipped with suitable furnishings for the comfort of the passengers occupying such suites. In such case access will usually be had from the vessel

from the staterooms of the ship and in case of accident officers of the ship will be detailed to each boat to man the same and to attend properly to the launching of the life boat after it has become submerged.

It will be understood that the life boats will be provided with the usual rings or chocks for the purpose of hoisting the same aboard the main ship or for launching the same so that the life boat may be used as a tender or launch.

It will be obvious from the description above given that the life boats are adapted equally well for use upon surface boats or upon submarines, that they may be launched in the usual manner from the deck of a ship if the same is floating and may be dropped precipitately into the sea without danger of drowning the passengers or swamping the life boat, thus avoiding the danger of being cast against the vessel by the sea. Furthermore the life boats may safely remain upon the main vessel until the same is submerged and thereafter be released in the manner aforesaid. When the life boat is used upon a submarine the same will serve not only as a life boat but as a diving bell, the life boat being returned to the main vessel by winding up the windlass cables which preferably are located on opposite sides of the longitudinal center of the submarine in order that the same may be properly positioned upon its original seat. When the sunken boat is reached the life boat may be properly positioned in the depression or recess forming its cradle by manipulation of a hand operated propelling mechanism the connecting bolts 25 connected to the deck of the ship and thereafter connection established between the life boat and the main vessel in the manner aforesaid.

If it is necessary for the life boat to leave the submarine because of weather conditions or otherwise the cables 58 and the air pipes 59 may be attached to suitable buoys which will mark the spot at which the submarine is located or if such buoys are not available the cables may be readily grappled by a searching vessel and thereafter used either to raise the submarine if not waterlogged or to tilt the same sufficiently to permit the usual hoisting cables to be attached.

It is to be understood that the embodiment of the invention disclosed herein is illustrative merely and is not restrictive. That the form of life boat may be varied, that the manner of its attachment to the vessel may be changed as found necessary or desirable and that various other modifications may be made, the gist of the invention residing in providing a vessel either submarine or surface vessel with an air tight

life boat provided with means whereby the 65 occupants of the main vessel may enter the life boat after the same has been submerged with means for closing the egress and ingress passages of the respective boats from within the life boat and means for releasing the life boat from the main ship.

Having thus described my invention, what I claim as new and desire to secure by Letters Patent, is:

1. In combination with a ship having an 75 egress passage, a submarine life boat having an air tight body provided with an ingress passage and means for detachably securing said life boat to said ship with said egress and ingress passages in connection, 80 and means for closing the ingress passage of the life boat from the interior of the life boat and automatically operating means adapted to be actuated upon the release of the life boat to close the egress passage of 85 the ship.

2. In combination with a ship having an egress passage, a submarine life boat having an air tight body provided with an ingress 90 passage and means for detachably securing said life boat to said ship with said egress and ingress passages in connection, and means for closing both the egress passage of the ship and the ingress passage of the life boat from within the latter and supplemental automatic means adapted to be actuated upon the release of the life boat to reinforce the closure of the egress passage of the ship.

3. In combination with a ship having a 100 hatch, a submarine life boat having an air tight body provided with a hatch adapted to be superimposed upon the ship's hatch, bolts for securing the life boat to the ship, independent means for closing the respective 105 hatches of the ship and life boat, a supplemental closure for the hatch of the ship comprising a counterweighted sliding plate, normally resting against the bolts which secure the life boat to the ship and adapted to be 110 released when the bolts are withdrawn substantially as described.

4. In combination with a ship having a hatch, a submarine life boat having a watertight body, and provided with a hatch 115 adapted to be superimposed upon the ship's hatch, bolts for securing the life boat to the ship, independently operable closures respectively for the hatches of the ship and the life boat and means for closing the bolt holes 120 in the ship when the bolts are withdrawn therefrom to release the life boat.

5. In combination with a ship having a hatch, a submarine life boat having a watertight body, and provided with a hatch adapted to be superimposed upon the ship's hatch, bolts for securing the life boat to the ship, independently operable closures respectively

- for the hatches of the ship and the life boat and means for automatically closing the bolt holes in the ship when the bolts are withdrawn therefrom to release the life boat.
- 5 6. In combination with a ship having an egress passage, a life boat having an air tight compartment detachably connected to said ship and provided with an ingress passage adapted to connect with the egress passage of the ship, a hose connected with said ship, a windlass upon said life boat adapted to receive and to coil up said hose whereby air may be supplied to the submerged ship
- 10

after the life boat has reached the surface of the water.

15

7. In combination with a ship, a plurality of intercommunicating submarine life boats having ingress passages connected with egress passages in said ship, means for closing the respective passages for releasing the life boats from the main ship and means for releasing the life boats from each other substantially as described.

In testimony whereof I have signed my name to this specification.

DAVID VICTOR REEVES.

Copies of this patent may be obtained for five cents each, by addressing the "Commissioner of Patents, Washington, D. C."
